VICTOR ANGERER, OF RIDLEY PARK, PENNSYLVANIA, ASSIGNOR TO WILLIAM WHARTON, JR. & CO., INCORPORATED, OF EASTON, PENNSYLVANIA, A CORPORATION OF PENNSYLVANIA.

SPRING BOX.

1,411,826.

Specification of Letters Patent.

Patented Apr. 4, 1922.

Application filed July 30, 1921. Serial No. 488,661.

To all whom it may concern:

Be it known that I, VICTOR ANGERER, a citizen of the United States, residing at Ridley Park, in the county of Delaware and 5 State of Pennsylvania, have invented certain new and useful Improvements in Spring Boxes, of which the following is a specification.

This invention relates to an improvement 10 in spring boxes for tongue switches in track work wherein the switch tongue is manually adjustable to control the direction of travel, and is automatically yieldable in reverse travel.

15 In spring boxes of this type it has heretofore been necessary to remove the cover to change the action of the spring box, or the action of the mechanism therein, and as this operation requires time and labor, it is highly 20 desirable that means be provided whereby the action can be changed in a simple, convenient manner from the outside of the box, and without the necessity of removing any portion thereof.

25 The invention generally stated involves a rocker throw element which is readily accessible through the top or cover of the box, and which can be shifted on its bearings from one position to the other through the 30 use of an ordinary bar without the necessity of removing any part of the box. The rocker cooperates with the yoke to shift the latter from one position to the other, the yoke in turn compressing a spring in its particular 35 movement to exert endwise pressure on the rod connected to the switch tongue, and thereby shift the latter in the direction of such pressure.

In the drawings:

40 Fig. 1 is a vertical sectional view of the improved spring box.

Fig. 2 is a section on line 2—2 of Fig. 1.

The improved box 1 is of substantially the ordinary type, having a cover 2 adapted for 45 convenient removal when necessary. The switch tongue 3 is connected by a rod 4 to the switch operating mechanism. This rod extends within and longitudinally of the box 1, and at spaced intervals is provided 50 with relatively free spools 5 and 6, adapted to be adjusted in their limit movement in opposite directions relative to the rod through nuts 7 threaded on the rod. The relatively inner, that is, the proximate ends 55 of the respective spools, have annular pro-

jecting heads 8 and 9 respectively, between which there is arranged a spring element 10 coiled about the rod. Thus, normally, the spools are held at the respective limits of movement permitted by the nuts 7, through 60 the spring 10.

A yoke 11 is slidably mounted in the box having at the respective ends, upstanding walls 12 and 13 formed with openings 14 to slidably receive the spools 5 and 6, the walls 65 of these openings engaging the respective heads 8 and 9 of the spools, so that the yoke walls or ends are arranged beyond the respective spool heads to thereby compel a movement of either spool in the direction of 70 the yoke, the yoke sliding freely on the spool nut operated in such movement. The yoke is provided at each end with upstanding abutments 15 and 16 respectively. The edges of these abutments toward the transverse center of the yoke, that is, their inner edges, are formed with curved surfaces 17 for a portion of their length, and recessed or curved bases 18 at their lower ends. The elements 17 serve as operating faces for the 75 yoke, while the elements 18 serve as locking recesses for the yoke.

The operation of the yoke is provided for through a rocker element 19 in the form of an arcuate transverse plate 20, having a substantial recess 21, preferably of angular formation. The rocker includes side plates 22 depending from the plate 20, and having at their lower ends outwardly and laterally arranged trunnions 23, which are accommodated in bearings 24 formed in the side walls of the box 1. The upper edges of the side plates 22 of the rocker are rounded at 25 to form bearing projections for cooperation with the faces of the yoke projections previously described.

The top of the box is formed by complementary cover plates 2, spaced relatively to provide a gap 27, through which is exposed the arcuate plate 20 of the rocker element, 100 the under proximate edges of the cover plates being contoured, as at 26, in coincidence with the curvature of plate 20. The length of the gap is such that in the relatively opposite positions of the rocker, the 105 recess 21 is at all times fully exposed through the gap 27. The top edges of the cover plates may, if desired, be bevelled as at 28, and the proportions are such, that in the relatively opposite positions of the rock- 110

er, one wall of the recess 21 is coincident with the edge of the gap 27 defined by the bevelled edge 28, so that the latter forms a guide for the convenient introduction of a 5 switch iron.

In operation, it will be apparent that in order to throw the switch, a switch iron is introduced into the recess 21 of the rocker, and the latter swung on its trunnions to the 10 opposite direction. This causes the operating face 25 of the rocker, which moves downwardly in this operation of the rocker, to ride on the face 17 of the adjacent yoke abutments, and in so riding force the yoke 15 longitudinally. In this movement, the spool opposite the end of the yoke being operated, that is, the spool 6 according to the present showing, is forced by the yoke to compress the spring 10, this compression continues until the tension of the spring overcomes the 20 weight of the switch and connected parts, and so shifts the switch tongue.

In the final movement of the rocker, the operating projection 25 rides into the recess 25 18 of the particular rocker abutment being engaged, and so temporarily locks the parts in the set positions.

Obviously the switch tongue, when set in one position or the other, may readily yield 30 in a reverse travel of the car, as neither spool is confined by the yoke, and in such reverse travel, the rod 4 will move, and the yoke engaged by the nuts 7 according to the direction of movement, will force the corresponding spool to compress the spring 10, the 35 opposite spool being held by the yoke.

After the car passes the switch, the spring being compressed in this movement of the switch point returns the switch point to its 40 previous set position.

It is apparent that the switch may be adjusted to either operative position through appropriate movement of the rocker element, and the latter may be operated through any 45 element capable of entering the recess 21, and having a length sufficient to provide for throwing the rocker element. Thus a change

in the switch is readily and conveniently accomplished without the necessity of removing any portion of the switch box, and without loss of time in such operation. The rocker element is, of course, designed to fit more or less snugly in the gap in the top of the switch box.

It is, of course, apparent that while two 55 spaced abutments at each end of the yoke is to be preferred, the operation can be effectively carried out through the use of but one abutment at each end.

Claims:

1. A spring box for switch tongues including a yoke for operating the switch tongue in either direction, said yoke having an abutment formed with an operating face and with a locking recess, and a rocker element having an operating projection to engage said face to operate the yoke, and to seat in said recess to lock the yoke in the operating position.

2. A spring box for switch tongues, including the yoke for operating the switch tongues in either direction, said yoke having an abutment formed with an operating face and with a locking recess, and a rocker element having an operating projection to engage said face to operate the yoke and to seat in said recess to lock the yoke in the operating position, said rocker element having a recess accessible through the top of the box to receive an operating bar.

3. A spring box for switch tongues, including a yoke for operating the switch tongue in either direction, said yoke having an abutment formed with an operating face and a locking recess, and a rocker element having an operating projection to engage said face to operate the yoke, and to seat in said recess to lock the yoke in the operating position, the top of the box being formed by complementary cover plates with an intervening gap, through which the rocker element is at all times accessible.

In testimony whereof I affix my signature.
VICTOR ANGERER.
